DESIGN.

H. S. KERR.

Patented Dec. 17, 1872.

No. 6,298.

H. S. Kerr

Interest

Arthur G. Munder Jr.

UNITED STATES PATENT OFFICE.

HUGH S. KERR, OF PHILADELPHIA, PENNSYLVANIA, ASSIGNOR TO DORAN, MAYBIN & CO., OF SAME PLACE.

DESIGN FOR CARPET.

Specification forming part of Design No. 6,298, dated December 17, 1872.

To all whom it may concern:

Be it known that I, HUGH S. KERR, of the city of Philadelphia, county of Philadelphia, State of Pennsylvania, have invented and produced a new and original Design for Carpets, of which the following is a specification:

The nature of my design is fully represented in the accompanying photographic illustration, to which reference is made.

Claim.

I claim as my invention—
The configuration of the design hereunto annexed, when applied to carpeting.

HUGH S. KERR.
